UNITED STATES PATENT OFFICE

137,615

DESIGN FOR A MEDALLION OR SIMILAR ARTICLE

Max J. Lewis, Forest Hills, N. Y.

Application January 28, 1944, Serial No. 112,359

Term of patent 7 years

(Cl. D29—23)

To all whom it may concern:

Be it known that I, Max J. Lewis, a citizen of the United States, residing at 69-17 Exeter Street, Forest Hills, county of Queens, and State of New York, have invented a new, original, and ornamental Design for a Medallion or Similar Article, of which the following is a specification, reference being had to the accompanying drawing, forming part thereof.

In the drawing:

Fig. 1 is a top plan view of the medallion or similar article showing my new design.

Fig. 2 is a side view of the same.

I claim:

The ornamental design for a medallion or similar article, substantially as shown.

MAX J. LEWIS.
